C. W. GARLAND.
MACHINE FOR CUTTING RAILWAY TIES.

Patented Jan. 9, 1900.

(Application filed Oct. 21, 1899.)

(No Model.)

UNITED STATES PATENT OFFICE.

CHARLES W. GARLAND, OF BLUEFIELD, WEST VIRGINIA, ASSIGNOR OF
ONE-HALF TO WILLIAM TAZEWELL POSTON AND EWELL L. WARREN,
OF LINDSEY, WEST VIRGINIA.

MACHINE FOR CUTTING RAILWAY-TIES.

SPECIFICATION forming part of Letters Patent No. 641,202, dated January 9, 1900.

Application filed October 21, 1899. Serial No. 734,385. (No model.)

To all whom it may concern:

Be it known that I, CHARLES W. GARLAND, a citizen of the United States, residing at Bluefield, in the county of Mercer and State of West Virginia, have invented certain new and useful Improvements in Machines for Cutting Railway-Ties; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements for cutting railway-ties, and especially to a frame having mounted therein rotary beveled cutting-blades set at suitable angles, means being provided to automatically engage the dog with the logs as they are passed through the feeding-trough to the cutters, and in the provision of additional means for holding the log in the trough while its sides are being hewed or cut to form the sides of the finished tie.

More specifically the invention resides in the provision of shafts having cutting-blades disposed at an angle on the beveled surfaces of the rotary cutter-heads disposed in reverse positions to each other and an endless chain carrying dogs, the spurs of which are caused to be forced into the end of a log in the feeding-trough by means of a pivoted pressure-hammer, the free end of which rests against a log while being cut; and after the log passes by the cutter-heads said pressure-bar adapted to swing down under the influence of a spring or by gravity and coming in contact with the following log to impart a longitudinal movement to the latter sufficient to cause the spurs of the dog to engage in the log, the pressure-bar after having kicked against the end of the log adapted to ride over the latter as the log advances toward the rotary cutter-heads.

To these ends and to such others as the invention may pertain the same consists, further, in the novel construction, combination, and arrangement of parts, as will be more fully described and claimed.

My invention is clearly illustrated in the

accompanying drawings, which, with the letters of reference marked thereon, form part of this specification, and in which drawings similar letters of reference indicate like parts throughout the several views, in which—

Figure 1 is a side elevation of my improved tie-cutting machine. Fig. 2 is a top plan view. Fig. 3 is a horizontal sectional view through the machine, and Fig. 4 is a detail view.

Reference now being had to the details of the drawings by letter, A designates a suitable framework, on which is mounted operating-shafts B, to which are keyed the two bevel-faced cutter-heads C. These cutter-heads have slots C' through their beveled surfaces, which slots are disposed at an angle less than a right angle to the outer flat ends of the cutter-heads, and in each of these slots a knife D is designed to be held in any suitable manner as in ordinary bench-planes. Located in the frame is the feeding-trough E, which runs longitudinally of the frame and between the cutter-heads. Mounted on the shafts F, near the ends of the frame, are sprocket-wheels G, over which an endless chain H travels. This chain has one or more dogs K formed out of links of the chain, or said dogs may form distinct plates, which are pivoted to the endless chain, and each dog has an upward projection K', the vertical edge of which has a series of teeth L, designed to engage with the end of a log and feed it forward to the cutter-head. Mounted adjacent to the rotary cutter-heads, slightly in advance of the same, are the standards M, to the upper ends of which is journaled a stub-shaft N, having keyed thereto the pressure-bar Q. Said pressure-bar has a laterally-extending arm R, to the outer end of which is connected a rod or chain S, the lower end of which is connected to a spring-bar T, one end of which is secured to the frame of the machine, as at T'.

The operation of my device will be readily understood when considered in connection with the drawings and the foregoing description and is as follows, viz: The logs are first placed upon the endless chain and are fed forward by means of the dogs catching in the rear end of each log, and when the forward end of a log strikes the pressure-bar Q the

free end of said pressure-bar is thrown up and the said bar rides on the upper surface of the log, serving to hold the same securely in place in the feeding-trough as said log is fed forward by the endless chain carrying the dog. After one log has passed between the rotary beveled cutters and is held securely in place in the feeding-trough during the cutting operation the pressure-bar returns to its normal position by the influence of gravity supplemented by action of the spring-bar described. It is designed to feed the logs upon the endless carrier at such distances apart that as the pressure-bar having held one log while it is being cut will fly down and kick against the following log, which will cause a slight longitudinal movement to be imparted to the same sufficient to drive the teeth L of the dog into the end of the log to securely hold the same as the log is being fed forward. As the log which has been kicked by the pressure-bar to engage the spurs advances toward the cutter-knives the pressure-bar will be pushed out of the path of the advancing log and serve to press on the upper surface of the log and securely hold it while the rotary cutters are beveling the opposite faces of the tie. It will be noted that the knives are set at such angles that a draw cut is afforded on the surface being hewed, as the heads carrying the knives are caused to rotate as the log is being fed forward.

Having thus described my invention, what I claim to be new, and desire to secure by Letters Patent, is—

35

1. In combination in a machine for cutting railway-ties, the frame, the beveled cutters, the shafts carrying the same, the cutting-knives seated in apertures in the beveled faces of said cutters, the feeding-trough, the endless chain and dogs carried thereby, the pivoted pressure-bar having a laterally-extending arm, a spring secured to said arm, said bar being disposed in the path of the advancing log, adapted to hold the latter in position while being cut and to kick against the end of the following log to engage the rear end of said log with the spurs of the dog as shown and described. 40

2. In combination with the endless chain, 45 and dogs carried thereby, and cutters mounted as described, a shaft mounted in suitable brackets on the frame of the machine, a weighted member depending from said shaft and normally resting in the path of the logs being fed forward by said chain, said member being adapted to be pushed out of the path of the advancing log by the latter, and to rest upon the log while being sawed, and then to drop off the end of the log and against 50 the end of a following log whereby the latter is driven against the teeth of the dog engaging the end of said following log, as and for the purpose set forth.

In testimony whereof I affix my signature 55 in presence of two witnesses.

CHARLES W. GARLAND.
